DESIGN FOR A MASQUERADE FLYING SUIT

Michael Couchman, New York, N. Y.

Application June 3, 1936, Serial No. 62,984

Term of patent 3½ years

To all whom it may concern:

Be it known that I, Michael Couchman, a citizen of the United States residing at New York city, in the county of New York and State of New York, have invented a new, original, and ornamental Design for a Masquerade Flying Suit, of which the following is a specification, reference being had to the accompanying drawing, forming a part thereof:

Fig. 1 is a front elevational view of a masquerade flying suit, showing my new design.

Fig. 2 is a rear elevational view of the same.

Fig. 3 is a side elevational view of the same.

Fig. 4 is a top plan view of the same.

I claim:

The ornamental design for a masquerade flying suit, as shown.

MICHAEL COUCHMAN.
